CLAIM

The ornamental design for a hair and body ornament, as shown.

DESCRIPTION

FIG. 1 is side elevational view of a hair and body ornament showing my new design;

FIG. 2 is a front elevational view; and,

FIG. 3 is a perspective view shown in a position of use on an ankle.

The broken line showing of hair in FIG. 1, an ankle in FIG. 3 and of beads and rings in FIGS. 1-3 are for illustrative purposes only and forms no part of the claimed design.

1 Claim, 2 Drawing Sheets
